UNITED STATES PATENT OFFICE.

WALTER S. ESTEY, OF WEBSTER, MASSACHUSETTS, ASSIGNOR OF ONE-HALF
TO A. J. BATES, OF WEBSTER, MASSACHUSETTS.

DETACHABLE CUSHION-HEEL.

SPECIFICATION forming part of Letters Patent No. 708,033, dated September 2, 1902.

Application filed March 11, 1902. Serial No. 97,777. (No model.)

To all whom it may concern:

Be it known that I, WALTER S. ESTEY, a citizen of the United States of America, residing at Webster, in the county of Worcester and State of Massachusetts, have invented certain new and useful Improvements in Heel Attachments, of which the following is a specification.

This invention relates to shoe-heels, and particularly to that class known as "cushion-heels."

The object of the invention is to produce a cushion-heel and means whereby the same may be attached to a shoe or detached when the heel becomes worn.

Furthermore, the object of the invention is to produce a heel-retaining device which may be manipulated for the purpose of applying or removing a heel without the exercise of skill, it being my purpose to produce heels having attaching means which ordinary purchasers may apply and remove.

Furthermore, the object of the invention is to produce a cushion-heel in which there are no metallic fasteners extending to the surface of the heel or which will be encountered as the heel is worn away.

A still further object of the invention is to produce a heel-fastening one member of which is embedded in the material at the time the heel is made and from which the member cannot with ordinary use be disconnected.

Finally, the object of the invention is to produce a heel and its fastenings which will possess advantages in points of simplicity, efficiency, and durability, proving at the same time comparatively inexpensive to produce.

With the foregoing and other objects in view the invention consists in the details of construction and in the arrangement and combination of parts to be hereinafter more fully set forth and claimed.

In describing the invention in detail reference will be had to the accompanying drawings, forming part of this specification, wherein like characters denote corresponding parts in the several views, and in which—

Figure 1 is a sectional view of a heel and the attaching parts. Fig. 2 is a perspective view of one of the parts. Fig. 3 is a perspective view of the other plate.

In the drawings, 1 indicates a shoe-sole, having secured thereto by any suitable fastenings, such as clinch-nails 2, the base-plate 3, said base-plate having an angular hole 4, 55 with the edges of the plate at the front and rear of the opening turned down slightly to form, with the sole, seats 5 for the reception of the tongues 6, which are carried by the heel 7. The tongues are integral with the resilient plate 8, said plate 8 being embedded in the material from which the heel is made. As cushion-heels are preferably of rubber, the plate 8 is seated when the vulcanizing process is being carried on, the rubber filling 65 in the spaces from which the tongues are struck. The plate 3 has ears 9, which lie against the edge of the sole where the plate is applied for the purposes of guides, that the plate may be attached in such relation to the 70 edge of the sole as to cause the heel to conform to the edge of the sole when the attaching means are in engagement.

In operation one tongue of the plate 8 is seated, and when sufficient pressure is applied the plate will bend slightly to permit its other tongue to be seated, thereby fastening the heel. When the heel is to be removed, the plate can be sprung outwardly until one of the tongues disengage, when the other may be withdrawn. The rear tongue may be slightly narrower than the front one in order that the front tongue may have a movement which will permit the rear tongue to disengage more readily when pressure is 85 exerted from the rear.

The construction, operation, and advantages will, it is thought, be understood from the foregoing description, it being noted that various changes may be made in the proportions and details of construction for successfully carrying the invention into practice without departing from its scope.

Having fully described my invention, what I claim as new, and desire to secure by Letters 95 Patent, is—

1. In a cushion-heel-attaching device, a base-plate having an angular aperture with the edge of the plate at the front and rear end of the aperture turned down to form seats, 100 a plate vulcanized in the heel and having tongues projecting from the inner surface,

said plates being adapted to be sprung to cause engagement of the tongues with the base.

2. In a cushion - heel - attaching device, a
5 base-plate secured to the sole of a shoe and
having an aperture with the front and rear
edge of the aperture turned down to form
seats, a plate embedded in the heel and hav-
ing a front and rear tongue projecting there-
10 from, the rear tongue being narrower than

the front tongue whereby the front tongue
will bend slightly to allow rear tongue to seat
with the base.

In testimony whereof I affix my signature,
in the presence of two witnesses, this 6th day 15
of March, 1902.

WALTER S. ESTEY.
